UNITED STATES PATENT OFFICE.

CHARLES F. BUSCHKE, OF MILWAUKEE, WISCONSIN, ASSIGNOR OF ONE-HALF TO LEON F. SNYDER, OF ROME, WISCONSIN.

INTERNAL-COMBUSTION ENGINE.

1,148,286.

Specification of Letters Patent. Patented July 27, 1915.

Application filed November 1, 1913. Serial No. 798,629.

To all whom it may concern:

Be it known that I, CHARLES F. BUSCHKE, a citizen of the United States, residing at Milwaukee, in the county of Milwaukee and 5 State of Wisconsin, have invented certain new and useful Improvements in Internal Combustion Engines, of which the following is a specification, reference being had to the accompanying drawing, forming a part 10 thereof.

The main objects of this invention are to prevent deposit of carbon on the working faces of the valves, and leakage and diminution of compression incident thereto; and 15 generally to improve the construction and operation of engines of this class.

It consists in the construction, arrangement and combination of parts as herein-after particularly described and pointed out 20 in the claims.

In the accompanying drawing like characters designate the same parts in the several figures.

Figure 1 is an axial section of a vertical cylinder four-cycle engine embodying the invention, showing the piston valve in the position it occupies on the suction stroke of the piston; Fig. 2 is a similar sectional view of a portion of the engine showing the piston valve in the position it occupies on the firing and compression strokes of the piston; Fig. 3 is a like view showing the valve in the position it occupies on the exhaust stroke of the piston; Fig. 4 is an enlarged 35 perspective view of one of the grid packing rings with which the piston valve is provided; and Fig. 5 is an axial section of the piston valve.

For the purpose of illustration the invention is shown and will be specifically described as embodied in a vertical cylinder four-cycle engine, specially designed for using crude or heavy oil which is injected directly into the engine cylinder on the suction strokes of the piston, air being admitted to the cylinder through a separate port controlled by another valve independently of the oil supply, but certain features of the invention are applicable to internal combustion engines of other types.

Referring to the drawing and particularly Fig. 1, *a* designates the engine cylinder of the usual or any suitable water-jacketed construction, *b* the piston and *c* the crank with

which the piston is connected by the pitman *d*, in the usual manner.

The cylinder is formed or provided on one side with a cylindrical valve case *e*, mounted with the cylinder as shown in the present instance, on a crank case *f*, which 60 constitutes the base of the engine, and with which both the cylinder and the valve case are in open communication at their lower ends. The valve case is preferably water-jacketed with the cylinder, as shown. 65

The valve case is connected with the upper end of the cylinder by a port *g*, and is provided on the opposite side with an exhaust port *h* below the port *g*. The upper end of the valve case is closed by a head which is 70 provided with an inlet port *i*.

A reciprocative piston valve *j* is fitted in the case *e* and controls the ports *g* and *h*. This valve may be actuated by any suitable connection with the crank shaft of the engine. In the present case a cam *k* is shown for this purpose. The cam is rotated in the direction indicated by the arrow at the rate of one revolution to every two revolutions of the crank shaft, and engages with a roller 80 *l* carried by the lower end of the valve stem *m* and held by a spring *o* in contact with the cam, the stem being held in axial alignment with the valve by a guide or guides *p* in the crank case. The cam shaft may be 85 connected, as indicated by dotted lines on Fig. 1, with the crank shaft, by sprocket wheels and a link belt *q*, or by any other suitable gearing.

The engine may be supplied with and 90 operated by carbureted air admitted thereto through the port *i*, especially when gasoline or light volatile fluid fuel is used, but for using heavier grades of oil, or less volatile fluid fuel, the engine is provided with a 95 special fuel supply valve and spraying device, as hereinafter described, the requisite supply of air for producing an explosive mixture being admitted through the port *i*.

The piston valve *j* is formed, as shown in Fig. 5, with a port *r* passing obliquely through it and arranged in a certain position of the valve, as shown in Fig. 3, to connect the cylinder port *g* with the exhaust port *h*. 100

To prevent the deposit of carbon on the working faces of the valve and valve case, the valve is provided with a number of ex-

pansive grid packing rings *s*, one of which is shown on an enlarged scale in Fig. 4. These rings are loosely fitted and confined in correspondingly shaped grooves in the valve, and each ring is composed of two parallel annular members *t* integrally connected with each other at intervals by members *u*, which form therewith jointless packing frames completely surrounding port openings *v*, corresponding in shape and size with the cross sectional area of the ports *g*, *h* and *r*. The valve is preferably provided with three of these rings, the upper two of which are each formed with two port openings *v* on opposite sides thereof, while the lower ring has one port opening on the outer side, adapted to register with the cylinder and exhaust ports *g* and *h* of the valve case in different positions of the valve, as shown 20 in Figs. 1, 2 and 3. The middle ring *s* is arranged so that the port opening *v* on the inner side thereof coincides with the inner end of the port *r*, and the lower ring *s* is arranged so that the port opening *v* on the outer side coincides with the outer end of the port *r*.

Outside of the ports *v* the annular members *t* of each ring are severed obliquely between adjacent connecting members *u*, to render them expansive or elastic, and to permit of their being sprung into place in the grooves in the face of the valve. Being normally of slightly larger diameter than the bore of the valve case, the rings *s* are contracted when they are inserted therein with the valve, and tending to expand, form and maintain tight joints between the face of the valve and the opposing face of the valve case around the ends of the port *r* which they surround, and around the ports *g* and *h*, with which the ports *v* in the rings register in different positions of the valve. The valve is also preferably provided, as shown, adjacent to its upper end, with a single or ordinary packing ring *w*.

For the heavier, less volatile grades of fuel, the cylinder head is provided with a spray nozzle *x*, which may be threaded therein, as shown, and is preferably formed in its outer end with two conical seats of different angles for a valve *y*, and in its inner end with small passages *z*, diverging from a point below the lower seat and opening into the cylinder. The valve *y*, which has two conical faces fitting said seats, normally closes the outer end of the passage in the spray nozzle, being seated by a spring *2*, surrounding the stem of the valve and bearing at its lower end against a collar *3* on the valve stem and at its upper end against an adjusting screw *4*, which is threaded in a yoke or bracket *5*, mounted on the cylinder head. The valve stem passes through and is guided in the screw *4*, a stuffing box 6 in the cover of a cylindrical case or chest

7, and a gland or sleeve *8* fitted in said chest.

The chest *7* is formed with or mounted on the cylinder head, and the gland or sleeve *8* is formed in its periphery with a groove 70 or channel *9*, and in its lower end with a cavity *10*, which is connected with the channel *9* by a number of small passages or openings *11*. The groove or channel *9*, surrounding the gland or sleeve *8*, and inclosed by the 75 case or chest *7*, forms an annular chamber which is supplied with oil through a pipe *12*.

Fluid tight joints are formed between the ends of the gland or sleeve *8* and the ends of the chamber in which it is fitted, by gas- 80 kets of suitable packing material. The cavity *10* in the lower end of said gland or sleeve forms with the outer end of the spray nozzle *x*, a valve chamber to which oil is supplied through the passages or openings 85 11 from the annular chamber *9*.

The valve *y* may be operated by any suitable connection with the cam shaft or other moving part of the engine. For this purpose a cam actuated lever *13* is shown in 90 Fig. 1. The lever *13*, formed with an opening through which the valve stem passes, is fulcrumed at one end on a bracket or arm *14*, attached to the cylinder head and engages with the collar *3*. At its other end the 95 lever *13* is pivoted to a suitably guided reciprocating rod *15*, which is provided at its lower end with a roller working with a cam *16* on the shaft of the cam *k*, as indicated by dotted lines in Fig. 1. The lever *13* is 100 fulcrumed on an eccentric pin *17*, by means of which the lift or opening of the valve *y* may be adjusted as desired.

In the operation of the engine, as the roller *l* traverses the low part of the cam *k* 105 between the points *18* and *19*, the piston valve *j* moves downward to the limit of its movement in that direction, uncovering the cylinder port *g* and establishing communication between it and the inlet port *i*, as 110 shown in Fig. 1. In this position of the valve the outer port *v* in the upper grid ring *s*, registers with the exhaust port *h* of the valve case, the annular members *t* and adjacent connecting members *u* of said ring 115 completely surround said port and prevent leakage between it and the upper end of the valve case. The single ring *w*, which in this position of the valve is between the ports *g* and *h*, further insures against leakage 120 between said ports around the intervening portion of the valve. This arrangement of the packing rings is specially advantageous in a multiple cylinder engine in which the several exhaust ports *h* are connected by a manifold, because in this position of the valve the exhaust from another cylinder is prevented not only from leaking into the upper end of the valve case 125 which is in open communication with the 130

cylinder through the port *g*, but also from depositing carbon on the faces of the valve and valve case outside of the port *v* in register with the port *h*.

5 As the roller *l* traverses that part of the cam *k* between the position in which it is shown in Fig. 1 and the point 19, the valve *j* is raised to the intermediate position in which it is shown in Fig. 2, covering and 10 sealing both the ports *g* and *h* and cutting off communication between the port *g* and the inlet port *i*. In this position of the valve the inner port *v* of the upper ring *s* registers with the cylinder port *g*, and the 15 outer port *v* of the middle ring *s* registers with the exhaust port *h*. As the roller *l* traverses that part of the cam *k* between the points 19 and 20, the valve *j* is held quiescent in the position in which it is 20 shown in Fig. 2 during the compression and firing strokes of the engine.

As the roller *l* traverses the high part of the cam *k* between the points 20 and 18, the valve *j* is shifted from the position in which 25 it is shown in Fig. 2 to its extreme upper position, as shown in Fig. 3, bringing the ends of the through port *r* in the valve into register with the cylinder port *g* and the exhaust port *h*. In this position of the 30 valve the inner port *v* of the middle ring *s* registers with the cylinder port *g*, and the outer port *v* of the lower ring *s* registers with the port *h*, and said rings thus tightly close and seal the space between the faces 35 of the valve and valve case around said ports, and effectively prevent the deposit of carbon on said faces, the spent gases passing from the cylinder during the exhaust stroke of the piston from the port *g* directly 40 through the port *r* to the port *h*. Thus only the walls of the valve port *r* and the comparatively small portions of the face of the valve corresponding with the port openings *v* in the middle and upper rings, are exposed to the exhaust of the engine, and the 45 valve which is lubricated by the splash of oil from the crank case or otherwise, is kept in working order without frequent grinding.

When a heavy grade of oil is used, it is 50 supplied through the pipe 12 by a pump or by gravity under sufficient pressure or head to keep the chamber 9 full. On the suction stroke of the piston when the valve *j* is in its lower position, establishing communication 55 between the ports *g* and *i*, the valve *y* is lifted from its seat by the cam 16, and a charge of oil is sprayed through the divergent passages *z* into the upper end of the cylinder in the path of the inrushing air 60 admitted through the port *g*. In passing from the chamber 9 through the small passages or openings 11 into the chamber 10, the oil is divided into small streams, and in passing between the upper conical face of 65 the valve and its seat it is reduced to a thin

film and is thus more readily converted into spray and vaporized in the nozzle which becomes heated by the operation of the engine. Issuing in a finely divided spray from the passages *x* into the cylinder, the 70 oil vapor meets and is thoroughly mingled with the air entering through the port *g*. When lighter and more volatile grades of fuel, such as gasoline, are used, the special oil supply valve *y* and spray nozzle *x* may 75 be dispensed with, the air supplied to the engine through the port *i* being carbureted in the usual or any suitable manner before it enters the valve case *e* and is admitted therefrom under the control of the valve *j* 80 into the cylinder. In either case, the operation and advantages of the valve *j* as hereinbefore described, are the same.

Various changes in the details of construction and arrangement of parts may be 85 made without departing from the principle of the invention as defined in the following claims.

I claim:

1. In an internal combustion engine the 90 combination of a valve case having inlet, exhaust and cylinder ports, a reciprocative piston valve fitted in said case and having a through exhaust port adapted in a certain position of the valve to register with and 95 connect the cylinder and exhaust ports of the case, and grid rings fitted in grooves in the valve and formed integrally with jointless packing frames which completely surround the ends of the exhaust port there- 100 through.

2. In an internal combustion engine the combination of a valve case having lateral cylinder and exhaust ports out of alignment with each other within the limits traversed 105 by the valve and an inlet port beyond the traverse of the valve, a reciprocative piston valve fitted in said case and having a through exhaust port arranged to register with and connect the cylinder and exhaust 110 ports, and grid rings fitted in grooves in the valve and formed with jointless packing frames completely surrounding the ends of the exhaust port therethrough and adapted to surround the cylinder and exhaust ports 115 of the case when the valve is closed on the compression and firing strokes of the engine piston.

3. In an internal combustion engine the combination of a valve case provided with 120 a port, and a reciprocative piston valve fitted in said case and provided with an expansive grid ring formed integrally with a jointless packing frame arranged to completely surround and seal said port in a certain position of the valve.

4. In an internal combustion engine the combination of a reciprocative piston valve having a through port opening through its 125 working face and spaced circumferential 130

and longitudinal connecting grooves surrounding the port opening and an expansive grid ring having severed annular members and integrally connecting members fitted in 5 said grooves and forming a jointless packing frame completely surrounding the port opening.

5. An expansive grid packing ring for a piston valve composed of two annular members and integral connecting members forming 10 a jointless packing frame completely surrounding a port opening in one side of the ring, the annular members being severed between adjacent connecting members outside 15 of the port opening.

6. In an internal combustion engine the combination of a valve case having lateral cylinder and exhaust ports out of alignment 20 with each other transversely to the axis of the valve and within the limits traversed by

the valve and an inlet port at one end beyond the traverse of the valve, and a reciprocative piston valve fitting in said case and provided with a through exhaust port having openings at the ends out of transverse 25 alignment with each other and adapted to register with and connect the cylinder and exhaust ports in one extreme position of the valve, said valve being adapted in its other extreme position to establish communication 30 between said inlet and cylinder ports and in an intermediate position to close both the cylinder and exhaust ports.

In witness whereof I hereto affix my signature in presence of two witnesses.

CHARLES F. BUSCHKE.
